United States Patent Office

Des. 220,782
Patented May 18, 1971

220,782

PORTABLE BATTERY TESTER

Albert Mazeika, Chicago, Ill., assignor to Milton
Manufacturing Company, Inc., Chicago, Ill.

Filed July 10, 1970, Ser. No. 23,894

Term of patent 14 years

Int. Cl. D10—11

U.S. Cl. D52—6

FIG. 1 is a perspective view of a portable battery tester, showing my new design;

FIG. 2 is a side elevational view thereof;

FIG. 3 is a rear elevational view thereof;

FIG. 4 is a top plan view thereof;

FIG. 5 is a bottom plan view thereof.

I claim:

The ornamental design for a portable battery tester, as shown.
